UNITED STATES PATENT OFFICE.

ARLINGTON MOORE, OF NEW YORK, N. Y., ASSIGNOR TO MOORE INVENTIONS CORPORATION, OF WORCESTER, MASSACHUSETTS, A CORPORATION OF MASSACHUSETTS.

SANITARY METAL CAN.

Application filed April 15, 1922. Serial No. 553,212.

My invention relates to sanitary metal containers and more particularly to metal cans adapted for containing food products and the like.

6 Broadly stated, it is the object of the present invention to provide a sanitary metal container which is capable of withstanding great pressure without distortion or leaks, and which may be made in large quantities 10 at high speed and with increased economy.

Heretofore it has been the practice to construct so-called sanitary tin cans by employing gaskets or the equivalent, between the portion of the can forming the wall, and 15 the portions forming the top and bottom respectively. Such gaskets have been maintained in position between adjacent portions of the metal parts of the container, it being intended that they should prevent access of 20 air and undesired escape of liquid contents of the container. It has been found, however, that, with seam constructions as heretofore used, the leakage frequently takes place notwithstanding the provision of gaskets, linings or the like within the can seams. 25

According to one feature of the invention, a metal container is provided in which such gaskets, linings and the like are eliminated and the metal parts of the container itself 30 are arranged and constructed in a novel manner to effectually prevent leakage.

Another feature relates to the provision of a metal container in which the component metal parts are secured together in a highly improved manner, whereby increased 35 strength is imparted to the can.

Another object relates to the provision of a metal container in which the various parts are brought into intimate contact by being 40 subjected to extremely high pressure, whereby a union of the parts is effected amounting substantially to a welding together and flowing of the metal under the high pressure.

Other objects will appear from the following description taken in connection with the 45 accompanying drawing in which Fig. 1 shows a side elevation of a metal container with parts broken away, embodying features of the invention. Figs. 2 to 7 show successive steps in the formation of the 50 container. Fig. 8 is a partial plan view of the can body, and Fig. 9 a section taken on the line 9—9 of Fig. 1.

Referring to the drawing, and more par-

ticularly to Fig. 1, there is shown one embodiment of my invention comprising a can body 10 which may be formed in any desired shape, having its ends substantially perpendicular to its longitudinal axis. As shown, a can body of cylindrical shape is provided. 55

The can body may be constructed in various ways, but is preferably made as shown herewith. The side seam of the can body is preferably of the lock or double seam form for the greater part of its length, as indicated in cross section at 11 in Fig. 9. Near the ends of the can body the side seam comprises the lap seam portion 12, and beyond the lap seam part 12 the edges of the sheet forming the can body preferably abut together, with little or no overlap, as shown at 13, 13, Fig. 8. The side seam may be soldered as is customary. If desired, an ordinary soldered lap seam may be substituted for the lock seam part 11, and various other side seam constructions may be used. 75

While the closure herewith described may be used only on the lid end of the can, and the can bottom may be secured in place in 80 any desired way, the top and bottom closures for the container are preferably formed in the same manner, and a description of one will suffice for both.

Referring to Fig. 2, the side wall 14 of the can body 10 is provided near its end with an outwardly extending shoulder 15, the end portion 16 of the can body being outwardly displaced or expanded with respect to the main portion 14 thereof a distance which is 85 preferably substantially equal to the thickness of the can body, as shown in Fig. 2, though such displacement may be more or less than this precise amount. The provision of shoulder 15 makes it possible to support 90 and hold the can firmly during the formation of the heading seam and also serves as a stop for the lid or closure when put in place in the can body. 95

The closure member 17 which may form 100 either the bottom or the top of the completed can, or both, as above indicated, is provided with a marginal flange 18 which is turned or flanged over so as to lie closely against the expanded portion 16 of the can body as indicated in Fig. 2 when the closure member 17 is inserted in place resting 105 against the shoulder 15 in the can body.

The enlarged end portion 19 of the can body 10 is longer than the flange 18, the relative dimensions being preferably about as indicated in Fig. 2.

5 The first step in forming the heading seam consists in turning the outer end 19 of the expanded end portion 16 of the can body, extending beyond the lid flange 18, inwardly over the edge of said flange, first as shown 10 in Fig. 3 and then as shown in Fig. 4, completing a turning movement of substantially 180°. The normally abutting edges, 13, 13, which temporarily lap past one another somewhat, as the parts are turned over (as 15 shown in Fig. 3), come again into abutting or substantially abutting position when the fold is completed as shown in Fig. 4.

Next the parts are turned inwardly a second time from the position shown in Fig. 4 20 to that of Fig. 5. The bend line for this operation preferably comes at substantially the middle of the lid flange 18, as shown in Fig. 5. When this is done a seam is formed about the end of the can, which comprises 25 five layers of metal, as shown in Figs. 5, 6 and 7 with the portion 19 originally forming the extreme outer edge of the can body in the center of the five-ply seam.

This marginal seam is subjected to enormous pressure applied both to the sides and 30 to the end of the seam, bringing the parts first into the relative positions shown in Fig. 6 and finally into the positions shown in Fig. 7. The pressure applied is preferably sufficiently great to cause an actual flowing or elongation of the metal, resulting in 35 the filling out of all open spaces in the seam with the metal to produce substantially a thick heavy ring about the can head, as shown at 20, Fig. 1. In this way the parts 40 are forced into such intimate contact that a junction is secured, equivalent in effect to the formation about the can head of a welded ring of substantial thickness and great mechanical strength.

The metal parts of ring-seam 20 being in 45 intimate contact, leakage is effectually prevented and all gaskets or linings as heretofore required are completely dispensed with. 50 The lap portion 12 of the side seam being only of about the height of the finished seam 20 indicated in Fig. 1, it will be seen that the preferably soldered lap portion 12 is not subjected to any bending or folding ac-

tion, but remains in its original liquid tight 55 and air tight condition.

It will be seen that in forming my improved seam certain portions of the metal making up the seam are turned over through an arc of as much as 270° to a complete circle 60 of 360°, part 19 of the can body, for example, being turned over in the finished position to the extent last named to extend substantially parallel to and in the same direction as in its original position as shown in Fig. 2. 65

The process of making the improved seam herein described is not claimed herein, but is claimed in my copending application Serial No. 553,213, filed on even date herewith.

An illustrative embodiment has been shown for the purpose of showing a way in which the invention may be practiced, but it is expressly understood that the scope of the invention is not to be limited thereby, reference being had to the appended claims for 75 that purpose.

I claim:

1. In a sheet metal can, a can body having a side seam comprising a principal lockseam portion, a lapseam portion and a portion at the end of the can body where the edges of the body material substantially abut against one another, said body being outwardly expanded and having a shoulder formed therein at about the junction between the lock and lap seam portions, a closure received in said can body and resting against said shoulder, and a heavy thick substantially ring-like seam uniting said body and closure comprising two reversely turned portions of the closure material and three reversely turned portions of the can body material with the extreme edge portions of the can body material centrally located in said seam, and said seam being compressed under high pressure applied both laterally and longitudinally to bring the parts thereof into intimate contact and provide a strong and tight seal without gaskets, linings or the like. 80 85 90

2. A can according to claim 1 in which the lap part of the side seam stops just short of the end of the completed can, whereby the lap part of the can body is not turned over in seaming the closure to the body. 100

In testimony whereof, I have signed my name hereto.

ARLINGTON MOORE.
